UNITED STATES PATENT OFFICE.

EMILE JOSEPH PEGLER, OF NEW YORK, N. Y.

TRANSPARENT REFRIGERATOR.

1,219,764.

Specification of Letters Patent. Patented Mar. 20, 1917.

Application filed March 23, 1916. Serial No. 86,149.

To all whom it may concern:

Be it known that I, EMILE JOSEPH PEGLER, a citizen of the United States, and a resident of the city of New York, in the county and State of New York, have invented new and Improved Transparent Refrigerators, of which the following is a full, clear, and exact specification.

This invention relates to improvements in display refrigerators; and an object of this invention is to provide a refrigerator of which even the transparent parts are entirely insulated.

The show windows and glass casings hitherto used for the display of perishable food-stuffs are neither sanitary nor economical. Then in spite of the fact that these windows and casings consume more ice or refrigerating fluid than an ordinary icebox with double wooden walls and saw-dust insulation therein, still it is difficult to keep in simple glass casings an even temperature at such a low degree as the perishable foods would require or where meat is stored away every night in a cold vault, and in the daytime hung up along the walls for display thus exposed to the market atmosphere, however it could be kept constantly in an insulated display refrigerator.

The new display refrigerator, having no surface which would be not insulated, fulfills a vital sanitary necessity.

This invention consists of construction, arrangement and combination of parts designed to produce display refrigerators with a transparent insulation which is built up of double glass walls containing a filler of water therein, or any transparent liquid. Water is a poor heat conductor, and of greater density than other insulation materials as mineral wool, saw dust and the like; but in spite of the favorable qualities of water as means for transparent insulation, it has never before been utilized for this purpose.

The way in which the foregoing objects are attained in the most practical and simple manner is described hereinafter with reference to the accompanying drawings in which similar characters denote corresponding parts throughout the several views and in which—

Figure 1 is a view in perspective of a

transparent display refrigerator with a sinkable bottom serving as a concealed door 55 thereof partly broken away to disclose the interior construction.

Fig. 2 is a partial horizontal section being taken on line 1—1 of Fig. 1.

Fig. 3 is a vertical section of Fig. 1 at line 60 2—2.

Fig. 4 shows in perspective the front of a modified form of this invention, in which the top, front and two end walls contain transparent panels.

Fig. 5 is a partial horizontal section of the refrigerator illustrated in Fig. 4, being taken on line 3—3 of Fig. 4.

Fig. 6 is a vertical section of Fig. 4, being taken at line 4—4 of Fig. 4.

Fig. 7 represents the partial elevation of a modified form of this invention, in which the display refrigerator has a row of transparent sliding doors at its front.

Fig. 8 is a vertical section taken on line 75 6—6 of Fig. 7.

Fig. 9 is the plan of what is shown in Fig. 7, taken at line 5—5 of Fig. 7.

Fig. 10 illustrates a modified form of this invention, being a perspective view of a 80 wooden display refrigerator with transparent panels serving as doors.

Fig. 11 is an enlarged vertical fragmentary section taken on line 7—7 of Fig. 10.

The refrigerator illustrated in Fig. 1 comprises a suitable rectangular receptacle having an outer shell *a* mounted on a base *b*. This shell *a* is built up of glass sheets like *c*, *c*¹, *c*² secured water-tight to metal angles of which is formed the frame-work *d*, *d*². One 90 side of shell *a* is partly cut away in the drawing to show that there is within a similar inner shell *a*¹ built of glass sheets like *c*³, *c*⁴ secured water-tight to the metal angle framing *d*³. Said inner shell is separated 95 from the outer shell by an interval of a few inches, the side and top surfaces of the shells thus kept in parallel spaced relation there is formed between both shells *a* and *a*¹ a uniform space as *f* which has a water-tight 100 metal bottom *e* securely resting on the top of base *b* as a lining thereon. At the top of the outer shell *a* two small holes *g* and *g*¹ are drilled through metal angle *d* and the corresponding edge of glass sheet *c*¹; the 105 space between the outer and inner shells

may be filled by a transparent fluid, like clear water, poured through one of the small holes, the other hole then serving to permit the escape of air. These outer and inner shells a and a^1 , containing the water filler between them, form the walls of this refrigerator, thus having at each surface a transparent insulation, except at the bottom, referred to hereinafter.

10 As shown in Fig. 3, the base b is provided with a top portion h which is designed to carry the contents of the refrigerator as a bottom thereof; this top portion h is a sinkable platform, not connected to the immovable top portion h^1 which surrounds the said sinkable platform h like a door-frame, and both are insulated by a non-transparent material as shown in Fig. 3. At a side-wall of base b in Fig. 1 there is one leaf of a hinged 15 door i which consists of two leaves, one of which is broken away in the drawing with a part of its frame, in order to disclose the interior of base b which serves as a shaft j for the sinking of the platform h . The said door i allows a free access to the platform h when it is lowered to the bottom of shaft j for the purpose to put on it the contents to be exhibited. The operation of lowering and lifting of this platform h might be 20 performed by hand and by any simple structure of some approved type adapted to sink area platforms, ashlifts and the like, and which consists in the present instance, for purposes of illustration, of the said shaft j containing at each of the four corners one set of pulleys, comprising two toothed wheels like l and l^1 near the wall of the shaft j one above the other so far apart as the space allows, and connected vertically by a 25 spoked chain k . Opposite to said wheel l is wheel l^2 , both connected horizontally by a common axis n which extends from wall to wall of the shaft and is rotatable in the bearings m . The upper wheel l^1 is similarly 30 connected by the upper axis n^1 . Consequently if one wheel like l^1 is turned it turns wheel l by chain k , and wheel l^2 by axis n , this mutual movement is transmitted to the other two sets of pulleys at the opposite end 35 of shaft j by wheel l^5 which is located on the inner end of the rotating axis n and turns the horizontally disposed chain k^2 thereon, which is similarly connected to axis n^2 ; thus a reciprocating rotation of the 40 four sets of pulleys is produced when one wheel is turned by hand through the crank O which is shown outside of the shaft, being an extension of an upper axis like n^2 , but if not in use can be taken off. To the vertically 45 rotating chains k and k^1 is fastened a horizontally disposed steel bar q , and in the same way is a similar bar q^1 secured to the chains k^3 and k^4 , these bars q and q^1 carry the sinkable platform h . A removable plug 50 p goes through the wall of base b into the

toothed wheel l^2 to stop the movement of the wheels when not in operation. Fastened to the outer line of the chains k and k^1 is shown a metal bar r which represents the counter-balance.

The refrigerator shown in front view in Fig. 4 is made up of the insulated wood framing v , v^1 , v^2 containing glass panels c^7 , c^8 , c^9 with transparent insulation therein, at the front and end walls and at the top of the refrigerator; each of these panels, built of two glass sheets like c^7 and c^{10} shown in Figs. 5 and 6, spaced a few inches apart in parallel relation and framed water-tight by a metal channel T , is in itself an independent rectangular flat block x and x^1 enveloped in the wooden frame v and v^2 . The said blocks x and x^1 are filled with clear water before set in the woodwork v and v^2 . If the panels are very large and the glass sheets c^9 and c^{12} comparatively too thin, the horizontal block x^1 can be left unfilled. Opposite to the front there is the rear wall v^4 which includes the hinged door t ; as shown in horizontal section in Fig. 5 and in vertical section in Fig. 6, this door t and the bottom u are insulated by some non-transparent matter.

Fig. 7 represents the partial elevation of a display refrigerator of which the front is transparent comprising sliding doors L and mullions or immovable panels N of similar appearance and alternatingly located, each of these doors and panels consists of a rectangular inner frame T^2 built of metal channel, which holds apart the outer glass sheet C and the inner glass sheet C^1 fastened thereto watertight. The frame T^2 and the edges of the glass sheets C and C^1 are securely covered by the outer metal channel-frame R . At the upper end of each of the doors L and panels N there are small holes g^2 drilled in the webs of the metal channels T^2 and R for the purpose of filling the space formed between the glass sheets C and C^1 with clear water of a temperature of about 90 degrees, preferably after the doors are put in place. To the bottom of door L are fastened two small supporting wheels J running in the steel groove E adapted for this purpose on the top cover of base B . Above the doors extends horizontally the guide H made of a flat steel bar to fit the groove of a small wheel P which rolls on it; the axis of this grooved wheel P is the two legged metal hanger F of which both legs are secured to the upper end of door L . By this means the door L , when moved, slides easily in spite of its size and weight.

Partitions, shelving, books, ice chest or refrigerating pipes are not shown in the drawings, their location being indifferent to the utility of this invention.

Fig. 10 is a wooden display refrigerator

having a front of which the upper part *y* is vertical, with transparent panels *w* therein to be opened as hinged doors; the lower front *z* is inclined and contains transparent panels *w*¹ which are pivoted doors. The construction of transparent insulation of these panels is shown in vertical section in Fig. 11 being an enlarged partial detail of door *w* in which two glass sheets *c*¹⁴ and *c*¹⁵ are spaced in parallel relation and framed water-tight by metal channel *T*³, set in the wooden frame *v*⁵, and filled with a transparent liquid through hole *g*³.

Although the forms of refrigerator hereinbefore described and shown differ somewhat in appearance and arrangement of parts, yet the method of transparent insulation of all the several forms is the same. The form varies in accordance with the requirements of particular uses; but in each of these forms the principle, which is the basis of this invention, is strictly kept, to produce transparent parts which are insulated, by employing the same elements, and thereby attain the same results.

I claim:

1. A transparent display refrigerator having inner and outer glass walls spaced apart to form a receptacle between them, an insulation filler consisting of transparent liquid in the receptacle and a frame for supporting the walls in position, the frame being pro-

vided with openings for filling and replenishing the liquid filler.

2. A refrigerating compartment having transparent panels made of inner and outer glass walls spaced apart to form a receptacle between them, an insulation filler consisting of transparent liquid in the receptacle and a water-tight frame for supporting the glass walls in position.

3. In a refrigerating compartment a transparent display panel having inner and outer glass walls spaced apart to form a receptacle between them, an insulation filler consisting of transparent liquid in the receptacle and a frame for supporting the glass walls in position.

4. A refrigerator body having transparent parts which are built of inner and outer glass sheets spaced apart to form a receptacle between them, an insulation filler consisting of transparent liquid in the receptacle.

5. A display refrigerator having inner and outer glass walls spaced apart to form a receptacle between them, an insulation filler consisting of transparent liquid in the receptacle, a frame for supporting the walls in position, an opening in the refrigerator, a closure for the opening, and means for moving the closure to and from closed position.

E. JOSEPH PEGLER.
